UNITED STATES PATENT OFFICE.

MAXIMILIAN RAHR, JR., OF MANITOWOC, WISCONSIN.

STORAGE SLING FOR VEHICLE SIDE CURTAINS.

1,409,239.

Specification of Letters Patent. Patented Mar. 14, 1922.

Application filed September 20, 1918. Serial No. 254,938.

To all whom it may concern:

Be it known that I, MAXIMILIAN RAHR, Jr., a citizen of the United States, residing at Manitowoc, county of Manitowoc, and 5 State of Wisconsin, have invented new and useful Improvements in Storage Slings for Vehicle Side Curtains, of which the following is a specification.

My invention relates to improvements in 10 storage slings or receptacles for vehicle side curtains.

The object of my invention is to provide an improved overhead receptacle for such curtains which will be easily accessible for 15 curtain adjusting and removing operations, and which, when the curtains are in place, will be adequately supported to prevent sagging, the curtains, (or upper wall of the curtain pocket), being pushed upwardly 20 against the under surface of the canopy, and the lower wall of the sling presenting a substantially straight, smooth, and even surface.

I contemplate storing the curtains directly under the vehicle top by means of a sling 25 which may have a pocket or curtain receiving chamber thereon, provided with a slack or expansible upper wall. One end of the sling may be detachably supported so as to drop down to facilitate the removal of the 30 curtains from the pocket or their replacement therein, the sling being supported or suspended in a substantially horizontal position between the bows of the vehicle top when in storage position.

35 In the drawings,—

Figure 1 is a view of my curtain receptacle or sling in curtain receiving position, showing the curtain receiving side.

Figure 2 is a sectional view on line 2—2 40 of Figure 1, with dotted lines showing the sling in curtain storing position.

Figure 3 is a view similar to Figure 2, but with the forward brace bow lifted in an initial canopy folding operation.

45 Figure 4 is a sectional view, drawn on line 4—4 of Figure 5, showing a modified form of pocket.

Figure 5 is a bottom view of the same.

Like parts are identified by the same reference characters throughout the several views.

In each form of construction illustrated in the drawings, the bottom of the sling is adapted to be supported, under tension, between a pair of bows, preferably between the forward brace bow 1, and the bow 2

which projects upwardly from the front seat of the vehicle. In Figures 1, 2, and 3, the bottom wall of the sling proper comprises a strip or sheet of canvas 5 secured to the front bow in any suitable manner, as indicated at 6. On the upper side of this sheet 5, (the side which is uppermost when the device is in curtain storing position), I preferably provide a curtain receiving pocket by attaching to the sheet 5 another sheet 7 of such dimensions that its end margins must be pushed inwardly to co-incide with the end margins of the sheet 5. The term end margins is used to designate the margins which are at the sides of the vehicle, or its canopy, the sheet extending transversely of the vehicle body. The two sheets 5 and 7 are secured together by stitching along their end margins, and also along the margin which constitutes the bottom of the pocket when the sling is in curtain receiving position, as shown by full lines in Figure 2, if the two sheets 5 and 7 comprise separate pieces of material. If they comprise a single piece of material, such material is so cut that the part forming the pocket wall 7 is a little longer than the part forming the pocket wall 5, and the two walls are integrally connected at the bottom, as shown in Figure 2, and it 85 becomes unnecessary to stitch these walls together along the bottom of the pocket.

The object of making the pocket wall 7 longer than the pocket wall 5 is to facilitate the bulging of the wall 7, while allowing the wall 5 to be drawn taut between the bows, thereby avoiding the unsightly appearance of an overhead pocket, as heretofore constructed.

Any suitable means may be provided for 95 securing or supporting the bottom wall 5 of the pocket between the bows. In the construction shown in Figures 1, 2 and 3, I employ a series of stays 10, preferably composed of strips of tape, and I connect each of these stays at one end with the forward brace bow, either by passing them about the bow or tacking them thereto by means of ordinary tacks or screws. These stays pass along the under surfaces of the pocket wall 5, and project beyond the pocket far enough to be connected with the bow 2, the latter being preferably provided with a corresponding series of stays or strips of tape 12, having buckles 13 on their free ends to receive the ends of the stays 10. With this construction, assuming the pocket to be in 100 105 110

curtain receiving position, as shown in Figure 2, the curtains may be inserted in the pocket at the top of the latter, and the stays may then be lifted to swing the pocket 5 toward a horizontal curtain storing position. The ends of the stays may then be passed through the buckles 13 and drawn taut, and held in such position by means of the buckles and the connecting straps or stays 12. In 10 case there is any tendency of the stays to stretch and permit a sagging of the pocket, the slack can be easily taken up by pulling the stays farther through the buckles, and again securing them under tension. The 15 end stays may be drawn through the buckles under sufficient tension to prevent flexion toward the center line of the vehicle canopy, drawing upon the ends of the pocket in opposite directions, or toward the sides of the 20 canopy. By properly storing the curtains in the pockets with the view of avoiding irregularities and allowing the curtains to rest in flat superposed positions throughout substantially the entire area of the pocket, 25 it is obvious that the sling will be adapted to hold the curtains against the under surface of the canopy, and within a space substantially equal to the thickness of the bow in its vertical dimensions.

30 In Figures 3 and 4, I have illustrated a form of construction in which the curtains may at all times be viewed by the occupants of the vehicle, and any tendency to displacement may therefore be observed. In this 35 construction, the bottom wall of the pocket is omitted, and a greater number of stays employed, the stays 10^a, constituting the tension stays, adapted to be engaged with the rear bow or with supporting buckles 40 connected with the rear bow as above described. The intermediate stays 20 are secured to the respective margins of the upper wall of the pocket. In this case, the upper wall 21 of the pocket is secured to the front 45 ends of all of the stays, and is adapted to be attached directly to the forward bow.

In the construction shown in Figures 4 and 5, the upper wall 21 of the pocket is made somewhat wider than the length of the 50 stays or tapes 20, and the margins are pushed toward each other until they co-incide with the ends of the stays 20, whereupon they are stitched thereto. They are correspondingly

stitched to portions of the stays 10 of equal length to that of the stays 20. If desired, 55 crossed stays 20 may also be extended diagonally across the upper wall of the pocket from one corner to another, as indicated by dotted lines in Figure 5.

In the modified form of construction 60 shown in Figures 4 and 5, the buckles are not essential, for the reason that the curtains may be readily inserted between the stays and the upper wall 21 of the pocket from either end of the pocket, and therefore it is 65 not necessary to allow the pocket to swing downwardly to facilitate inserting the curtains. The stays 10^a may therefore be directly and permanently connected with the bow 2, as shown in Figure 4, it being possible to detach them by withdrawing the tacks or screws whenever it becomes necessary to take up slack due to the stretching of the tapes.

I claim:—

1. The combination with a vehicle canopy top, of a curtain receiving pocket having one of its walls connected with the top along one margin and having another wall connected with the first mentioned wall along the remaining margins, said walls being separable along one margin to permit the insertion and removal of curtains, and means for detachably supporting the closed portion of the 80 pocket from said canopy top.

2. The combination of an automobile having a canopy top, of a curtain receiving pocket comprising two members secured together along three of their sides and having an entrance opening adjacent the remaining side, said pocket being attached to the canopy top along one edge of one of said members adjacent the entrance opening of said pocket to provide a support for the pocket with the entrance opening uppermost 90 when the pocket is swung into substantially vertical position, and means for retaining the pocket in substantially horizontal position adjacent the canopy top after the storage or removal of curtains.

In testimony whereof I affix my signature in the presence of two witnesses:

MAXIMILIAN RAHR, JR.
